UNITED STATES PATENT OFFICE.

HENRY CAMPBELL JENKINS, OF HOVE, ENGLAND.

DEVICE FOR COMPRESSING VALVE SPRINGS OF INTERNAL-COMBUSTION ENGINES AND FOR LIKE PURPOSES.

Application filed May 4, 1926, Serial No. 106,595, and in Great Britain December 7, 1925.

This invention relates to a device for lifting and compressing the valve springs of internal-combustion engines, whether on or off the said engines, and other springs, of 5 the type which comprises a pair of bifurcated jaws between which the said springs are compressed for removal or replacement, placing between clips and other purposes, the said jaws being compelled to move partly 10 parallel to each other by means of suitable link-work when being opened or closed.

The object therefore of this invention is to construct a spring lifter and compressor which is operated by handles instead of a 15 nut and screw which will compress a spring by either of the methods above mentioned.

I attain this object by the mechanism illustrated by the accompanying drawings in which:—

20 Fig. 1 shows my improved device closed.

Fig. 2 shows the device with the jaws open and a spring between them ready for compression.

Fig. 3 shows the device with the jaws 25 partly closed and the spring fully compressed between them.

Fig. 4 shows a spring being compressed between the upper jaw of the device and a part of the engine, the lower jaw bearing 30 another part of the engine.

Fig. 5 shows an alternative method of connecting the handles to the arms carrying the jaws.

Fig. 6 is a plan of one of the arms and 35 jaw.

The same numerals denote the same parts throughout.

1 and 2 are flat metal arms provided at one end with bifurcated jaws 3 and 4 at 40 right angles to the plane of the arms 1 and 2.

The arms 1 and 2 and the jaws 3 and 4 are compelled to move parallel to each other when the jaws are approaching or receding from each other by means of the crossed 45 links 5 and 6 which are pivoted to each other at 7 and to the arms 1 and 2 by pivot pins such as bolts, screws or the like, hereinafter referred to as bolts 8 and 9.

The links 5 and 6 are also pivoted by 50 means of bolts 10 and 11 to the crossed handles 12 and 13, the bolts 10 and 11 sliding in the slots 14 and 15 in the arms 1 and 2. The bolts 10 and 11 may have brass collars thereon to enable them to slide easily 55 in the slots 14 and 15.

The jaws 3 and 4 are preferably stepped or cranked as shown, and by bolting the links 5 and 6 to the arms 1 and 2 and to the handles 12 and 13, the jaws may be reversed when desired by removing the bolts 60 and turning the jaws upside down and replacing the bolts.

The jaws are shown in different positions in the figures. In Figs. 1, 4 and 5 the steps in the jaws are parallel to each other and 65 facing the same way.

In Figs. 2 and 3 the steps are shown facing the same way but in the opposite direction to that shown by Figs. 1, 4 and 5, the jaws having been reversed.

The handles 12 and 13 are curved and preferably shaped as shown, and when the jaws are closed the handles assume the position shown by Figs. 1 and 5, and cross one another behind the pivot 16.

On pressing the handles together, the first movement of the handles opens the jaws, see Fig. 4, and to fully open the jaws the handles are pulled apart and assume the position shown by Fig. 2.

On again pressing the handles together the jaws are caused to approach one another, see Fig. 3, the handles again crossing one another behind the pivot 16.

A locking loop or ring 17 may be slipped 85 over the handles to secure them in the position shown by Figs. 3 and 4 to hold a spring between the jaws when compressed, or between the jaw and a part of the engine, leaving the hands free to remove the cotter 90 and valve.

In some cases I may pivot the handles to the front ends of the arms 1 and 2, as shown by Fig. 5.

In case it is desired to pivot the handles 95 to the front ends of the arms 1 and 2, instead of pivoting them to the rear ends of the links 5 and 6, this may be done by removing the bolts 10 and 11 and bolting the handles to the links and front ends of the 100 arms with the bolts 10 and 11, and replacing the said bolts with the bolts 6 and 9 to secure the rear ends of the links to the arms.

This method of attaching the handles gives a direct pressure on the jaws and the 105 crossed links merely keep the arms 1 and 2 parallel to each other.

By means of this invention an easy and instantaneous lifting and compressing action may be obtained and the device may be con- 110

structed for various sizes of springs within wide limits.

I claim:-

1. In a device for compressing valve spring of internal-combustion engines and for like purpose, the combination of two longitudinally slotted arms having a bifurcated jaw at one end of each arm in a plane at right angles to the plane of the arms, with 5 a pair of crossed links pivoted to one another at their point of intersection and detachably pivoted at one end to the said arms, the other end of said links being provided with bolts or the like sliding in the slots in said arms, and two curved crossed handles pivoted to 10 one another at their point of intersection, the shorter ends of the said handles being adapted to be pivoted to the sliding ends of the crossed links by means of the said bolts or the like or to the bolts or the like by 15 which the said links are pivoted to the front 20

ends of said arms, the said handles crossing one another behind their point of intersection, all substantially as set forth.

2. A device for compressing valve springs 25 of internal-combustion engines and for like purposes, comprising arms provided with bifurcated jaws moving parallel to one another, curved crossed handles detachably pivoted to said arms, said handles being pivoted to one another at their point of intersection.

3. A device for compressing valve springs 30 of internal-combustion engines and for like purposes, comprising reversible arms provided with bifurcated jaws moving parallel to one another, curved crossed handles detachably pivoted to said arms, said handles being pivoted to one another at their point of intersection and re-crossing one another 35 behind the point of intersection.

H. CAMPBELL JENKINS.
